LUBRICATING APPARATUS

Johan Ferdinand Julius Clementson, Malmo, Sweden, assignor to C. & S. Clementson, Malmo-Limhamn, Sweden, a firm composed of Carl Clementson and Sven Clementson

Application June 2, 1936, Serial No. 83,156
In Germany October 9, 1935

7 Claims. (Cl. 123—196)

This invention relates to an apparatus for automatically feeding a lubricating oil, especially an oil having corrosion-inhibiting properties, to the cylinders of an internal combustion engine, in which the oil is mixed with air and the mixture is drawn in through the intake manifold of the engine by the suction produced when the engine is running.

It is well known that the wear of the cylinders of an internal combustion engine is greatest during the starting period before the cylinder walls have been heated to their normal running temperature. In order to prevent, or reduce, this wear the lubricating oil should be introduced into the cylinders in a relatively large quantity from the moment of starting the engine when cold until the engine cylinders have attained substantially their normal running temperature. The oil supply to the cylinders should then be decreased and varied in dependence upon the load of the engine in such a manner that the oil supply to the engine increases and decreases with the load of the engine.

The object of the invention is to provide an apparatus by which the supply of the oil is controlled automatically so as to fulfill the requirements above referred to. A further object of the invention is to provide an apparatus of this kind which is of simple construction and reliable in its action. Further objects of the invention will appear from the following detailed description of a preferred embodiment thereof.

In the drawing:

Fig. 1 is an elevation, partly in section, of the preferred embodiment of the apparatus.

Fig. 2 is a plan view of parts shown in Fig. 1. Referring to the drawing, 1 designates a bellows and 2 a coiled spring which is located in the bellows and tends to keep it extended. At one end the bellows 1 is secured to a part 3a of a housing 3, the movable opposite end of the bellows being connected to a sliding rod 4 guided in a hole 5 in a part 3b on the housing 3. The rod 4 is provided with stop pins 4a and 4b coacting with the part 3b for limiting the sliding movement of the bar 4 in both directions. The bar 4 is also provided with a projecting pin 6 engaging a bifurcated arm 7 secured to the spindle 8 of a needle valve 9 which is screwed into the housing 3 and controls the opening of an oil conduit 10 into a mixing chamber 11 formed in the housing 3. The oil conduit 10 is connected to an oil container 10a by means of a pipe 10b. A packing 12 is provided for the spindle 8 of the needle valve for preventing entry of false air. An adjustable valve 13

screwed into the housing 3 provides an adjustable air inlet for an air conduit 14 leading to the mixing chamber 11. From the mixing chamber 11 leads a conduit 15 which is connected by means of a pipe 16 to the intake pipe or manifold 17 of the engine at a place between the throttle 19 of the carburetor 18 and the cylinder block 20 of the engine.

The housing 3 is also provided with a second air inlet 21 which is adjustable by means of an adjustable valve 22 and is controlled by means of a valve flap 23 coacting with a seat 24 screwed on the top of the adjustable valve 22. The flap 23 is pivoted at 23a and provided with a bent arm 23b projecting above the rod 4. The rod 4 is provided with an adjustable abutment 25 having an inclined cam surface 25a adapted to coat with the arm 23b in such a manner that the flap 23 is raised by the action of the inclined cam surface 25b on the arm 23b when the rod 4 is moved to the right in Fig. 1. When the bellows 1 is in the position shown in full lines in Fig. 1 the flap 23 is held on the seat 24 by means of a spring 26, thereby closing the second air inlet 21.

The bellows 1 is connected by means of a piping 27 to a chamber 28 secured on the cylinder block 20. Pivoted at 29 to an ear 30 in this chamber 28 there is a lever 31 provided at one end with a valve 32 controlling a conduit 33 connecting the chamber 28 to the intake manifold 17 of the engine. Normally the valve 32 is held against its seat by means of a spring 34 which is supported between a fixed part 35 and a collar 36a or the like on a slidable pin 36 acting on the other end of the lever 31. In the chamber 28 there is also provided a thermostatic element, for instance in the form of a bellows 37 filled with a volatile liquid which, when heated, expands and extends the bellows, whereby the latter is caused to actuate the lever 31 and open the valve 32.

The operation of the apparatus is as follows:

When starting the cold engine it is desirable that a relatively large quantity of lubrication oil is introduced into the cylinders of the engine from the very starting moment until the engine cylinders have attained substantially their normal running temperature, in order to prevent, or reduce, the great wear which otherwise takes place during this period and which, as known, is caused by the highly corrosive action of the acid condensates which are formed in the engine cylinders and deposited on the walls thereof before they have attained substantially their normal running temperature. This relatively rich supply of the corrosion-inhibiting lubricating oil

from the moment of starting the engine until the cylinder walls have attained substantially their normal running temperature is effected in the following manner. When the engine is started it 5 produces a vacuum in the intake manifold 17, and by means of the pipe 16 and the conduit 15 this vacuum is transmitted to the mixing chamber 11 so that oil is drawn from the container 10 into the mixing chamber 11 in a relatively large 10 quantity due to the fact that valve 8 is in its most open position, and simultaneously air is drawn in through the valve 13 and the conduit 14. The air and oil are mixed in the mixing chamber, and the mixture is drawn into the engine cylinders 15 through the conduit 15, the pipe 16 and the intake manifold 17. The air drawn in through the valve 13 serves the purpose of subdividing the oil and taking it along to the engine cylinders where the oil is deposited on the cylinder walls. 20 When the engine has attained substantially its normal running temperature the thermostatic element 37 opens the valve 32 so that the vacuum in the intake manifold 17 is transmitted through the conduit 33, the chamber 23 and the pipe 27 25 to the bellows 1 which thereby is caused to draw together to a degree corresponding to the occasional degree of said vacuum which, as is well known, varies within wide limits according to the speed of the engine and the setting of the gas 30 throttle 19. At increasing load on the engine the speed thereof decreases, even if the throttle is fully open, so that the vacuum in the intake manifold decreases to a low value, for instance 3 to 4 cm. Hg. At such a low value of the vacuum 35 the bellows 1 is kept wholly expanded by the spring 2 so that the rod 4 by means of the pin 6 and the arm 7 keeps the needle valve 9 screwed up in its most open position, whereby a relatively rich supply of oil to the engine cylinders is obtained in spite of the relatively low vacuum in 40 the intake manifold of the engine. At decreasing load on the engine the speed thereof increases, and the throttle 19 may be closed more or less. As a consequence hereof the vacuum in the intake 45 manifold increases, whereby the bellows is caused to draw together to a degree corresponding to the increase of the vacuum. When drawing together the bellows 1 pulls the bar 4 to the right in Fig. 1 so that the bar by means of the pin 6 50 and the arm 7 rotates the spindle 8, thereby screwing down the needle valve 9 so that the oil supply to the mixing chamber 11 and through the conduit 15, the pipe 16 and the intake manifold 17 to the engine cylinders decreases as the vacuum 55 in the intake manifold of the engine, for instance when the engine is running idly and the gas throttle 19 is almost wholly closed, at which occasion the vacuum may be as high as about 60 50 cm. Hg, the bellows draws together wholly, whereby the rod 4 is moved in the position shown by dotted lines in Fig. 2, in which position the needle valve 9 is screwed down to almost wholly closing position. Due to said great vacuum, however, the suction effect in the conduit 15 is increased so much that even the very small passage 65 for the oil, which is left by the needle valve 9 and which is necessary for upholding the oil column in the conduit from the oil container 10a 70 to the mixing chamber 11, would result in too great a supply of oil to the engine cylinders. In order to moderate the suction effect in the mixing chamber and thereby to moderate the oil supply at such high vacuum the valve flap 23 is opened 75 when the bellows 1 draws together under the

action of the high vacuum, in that the arm 23b is lifted by the inclined cam surface 26a. Thus the air inlet 21 is opened so that a stream of air which is moderated to a suitable value by adjustment of the valve 22, enters the conduit 15 and 5 moderates the suction effect in the mixing chamber 11. Due to the fact that the abutment 25 is adjustable on the rod 4 the operation of the valve 23 for moderating the suction effect in the mixing chamber 11 can be suited according to the 10 demands for different engines.

The construction can be varied and modified in several respects without departing from the essential features of the invention. For instance there may be used instead of the bellows a dia- 15 phragm or a piston movable in a cylinder or the like, and a thermostatic element of another kind than the bellows 37, for instance a bimetallic spring, may be used for operating the valve 32 in dependence upon the temperature of the 20 cylinder block or of the cooling water circulating therethrough.

What I claim and desire to secure by Letters Patent is:—

1. In an apparatus for automatically feeding 25 a lubricating oil to the cylinders of an internal combustion engine by the suction created in the intake manifold thereof, a mixing chamber having an air inlet, an oil inlet which is adapted to be connected to an oil supply tank, and an outlet which is adapted to be connected to the intake manifold of the engine, an operable valve in said mixing chamber for controlling the oil inlet thereof, means operable by vacuum and adapted to be connected to the intake manifold 30 of the engine for operating said valve in closing direction at increasing and in the opposite direction at decreasing vacuum in the intake manifold of the engine, and thermostatically controllable means for shutting off said valve operating 35 means from the intake manifold of the engine, whereby to keep said valve operating means inoperative until the engine has attained substantially its normal running temperature.

2. In an apparatus for automatically feeding 45 a lubricating oil to the cylinders of an internal combustion engine by the suction created in the intake manifold thereof, a mixing chamber having an air inlet, an oil inlet adapted to be connected to an oil supply tank, and an outlet adapted 50 to be connected to the intake manifold of the engine, a rotatable valve threaded in said chamber for controlling the oil inlet thereof, a slide- 55 able rod, means operable by vacuum and adapted to operate said slideable rod in one direction at increasing and in the opposite direction at decreasing vacuum in the intake manifold of the engine, said valve being operatively connected to said slideable rod so as to be rotated thereby from fully open position in absence of vacuum 60 in the intake manifold to slightly open position at increase of vacuum in the intake manifold to its highest value, and thermostatically controllable means for rendering said rod operating 65 means inoperative until the engine has attained substantially its normal running temperature.

3. An apparatus as claimed in claim 2, in which said rod operating means comprises a bellows adapted to be set in communication with the intake manifold of the engine and having a fixed end and a movable end to which said slideable rod is attached, and a coiled spring inside said bellows, said spring tending to keep said bellows extended.

4. In an apparatus for automatically feeding an oil, especially an oil having corrosion-inhibiting properties, to the cylinders of an internal combustion engine by the suction produced thereby when running, an oil supply conduit leading to the intake manifold of the engine, a rotatable needle valve in said conduit for controlling the oil flow therethrough, said valve having a threaded spindle, a bifurcated arm secured to said spindle, a slidable rod having a projecting pin engaging said bifurcated arm, a bellows having a fixed end and a movable end to which said slidable rod is attached, a coiled spring inside said bellows, said spring tending to keep said bellows in an extended position in which said needle valve is fully open, means for transmitting vacuum from the intake manifold of the engine to said bellows to move said movable end thereof against the action of said spring in order to rotate said needle valve in closing direction, said vacuum transmitting means comprising a piping having a thermostatically controlled valve therein and connecting the interior of said bellows with the intake manifold of the engine.
5. An apparatus as claimed in claim 4, in which said oil supply conduit is provided with an adjustable air inlet, and in which there is provided an air valve for said air inlet, means for normally keeping said air valve in closed position, and means adapted to open said air valve when the vacuum in said intake manifold exceeds a certain value.
6. In an oil feeding apparatus as claimed in
- claim 4, an air inlet to said oil supply conduit at a place thereof located between said needle valve and said intake manifold, an adjustable air valve in said air inlet, a seat on top of said air valve, a pivoted valve flap adapted to coact with said seat and liftable therefrom for allowing air from the outside atmosphere to flow into said air inlet through said air valve, a bent arm on said valve flap, said arm extending to said slidable rod, an adjustable abutment on said rod having an inclined cam surface adapted to engage said bent arm and lift said flap when the vacuum transmitted to the inside of said bellows from said intake manifold exceeds a certain value.
7. An apparatus as claimed in claim 4 in which said thermostatically controlled valve comprises a housing connected in said piping and secured on the cylinder block of the engine, there being provided a lever in said housing, a valve on one end of said lever for controlling communication through said piping between the interior of said bellows and said intake manifold, a spring actuated rod tending to keep said lever with said valve in a closed position, and a thermostatic element having a volatile liquid therein for expanding said thermostatic element as soon as the temperature of the engine cylinders increases, said thermostatic element being adapted to engage said lever as soon as a certain temperature is attained, whereby to open said valve against the action of said spring actuated rod.
